United States Patent Office.

NICHOLAS S. VEDDER, OF TROY, NEW YORK.

Design No. 3,860, dated February 22, 1870.

DESIGN FOR A STOVE-PLATE.

The Schedule referred to in these Letters Patent and making part of the same.

To all whom it may concern:

Be it known that I, NICHOLAS S. VEDDER, of the city of Troy, in the county of Rensselaer, and State of New York, have invented and produced a new and original ornamental Design for Plates of a Cooking-Stove, of which the following is a specification, reference being had to the accompanying photographic illustration.

The distinguishing feature of this design is a series of ornamental bars, *a*, shaped and arranged upon a door or doors, or on a plate or plates of a cooking-

stove, so as to present an appearance like that represented in the aforesaid photograph.

What I claim as my invention or production, and desire to secure by Letters Patent, is—

The design for a door or doors or plate or plates of a cooking-stove, as herein shown and described.

In testimony whereof, I hereunto set my hand this 28th day of December, 1869.

Witnesses: NICHOLAS S. VEDDER.
